UNITED STATES PATENT OFFICE.

WILLIAM W. FERREE, OF HARDIN, MISSOURI, ASSIGNOR OF ONE-HALF TO
J. F. FLOYD, OF SAME PLACE.

DRAFT-EQUALIZER.

SPECIFICATION forming part of Letters Patent No. 610,267, dated September 6, 1898.

Application filed January 27, 1898. Serial No. 668,183. (No model.)

To all whom it may concern:

Be it known that I, WILLIAM W. FERREE, a citizen of the United States, residing at Hardin, in the county of Ray and State of Missouri, have invented a new and useful Draft-Equalizer, of which the following is a specification.

The invention relates to improvements in draft-equalizers.

10 The object of the present invention is to improve the construction of draft-equalizers and to provide a simple, inexpensive, and efficient device adapted to be applied to two-horse vehicles and capable of equalizing the 15 draft between a weaker and a stronger horse.

A further object of the invention is to dispense with the pivot-bolts of singletrees and doubletrees and to avoid weakening the latter by perforating them for the reception of 20 such bolts.

The invention consists in the construction and novel combination and arrangement of parts, as hereinafter fully described, illustrated in the accompanying drawings, and 25 pointed out in the claims hereto appended.

In the drawings, Figure 1 is a plan view, partly in section, of a draft-equalizer constructed in accordance with this invention and shown applied to the singletrees and doubletree of a pole or tongue. Fig. 2 is a detail perspective view illustrating the construction of the connection between the doubletree and the pole. Fig. 3 is a horizontal sectional view of the same. Fig. 4 is a detail perspective 35 view of the rack-bar of the doubletree. Fig. 5 is a detail view of the central casing.

Like numerals of reference designate corresponding parts in the several figures of the drawings.

40 1 designates a doubletree arranged within a central casing 2, mounted upon a pole or tongue 3 and consisting of top and bottom plates 4 and 5 and front and rear walls 6 and 7. The bottom plate is provided with suitable perforations and is bolted or otherwise secured to the pole or tongue, the fastening devices being preferably located beyond the front and rear walls 6 and 7, as shown, in projecting portions of the bottom plate. The 45 front and rear walls 6 and 7 are curved and present convex faces to the front and rear

edges of the doubletree, and the front wall is provided at its inner convex face with teeth 8, forming a curved rack and meshing with the teeth of a straight rack-bar 9. The rack-bar 9 is bolted or otherwise secured to the front edge of the doubletree, and by gearing the doubletree with the casing, as shown, the fulcrum-point is shifted when the doubletree swings, making the forward arm or side 60 shorter than the other, whereby the rear or weaker horse is given an increased leverage and the draft between it and the stronger horse equalized, so that the weaker or rear horse can readily draw the doubletree to its 65 proper position at right angles to the pole or tongue.

The rear wall 7 presents a smooth convex face to the doubletree, and the front and rear walls form flaring side openings for the casing and permit a free limited swing of the doubletree.

By arranging the doubletree in the casing 2, as shown, the pivot-bolt is dispensed with, and it is unnecessary to perforate the doubletree for the reception of the bolt. The strength and durability of the doubletree are thereby increased, and as the swing of it is limited stay straps or chains are dispensed with.

Singletree-casings 10 are mounted on the 80 ends of the doubletree and receive singletrees 11, which operate similar to the doubletree, the singletree-casings being principally employed to avoid perforating and weakening the singletrees by dispensing with their bolts. 85 The singletree-casings, which are suitably secured to the doubletree, are composed of top and bottom plates and curved front and rear walls 12 and 13, the front wall being provided at its inner face with teeth to form a curved 90 rack. The singletrees are provided at their front edges with straight rack-bars 14, which mesh with the curved racks of the casings 10, and the rear walls 13 present smooth convex faces to the rear edges of the singletree. The 95 singletree-casings are also applicable to the singletree of a pair of thills and will dispense with the pivot-bolt of the same.

The invention has the following advantages: The draft-equalizer is simple, strong, and 100 durable and adapted to be applied to singletrees and doubletrees. It obviates the ne-

cessity of employing pivot-bolts, and it increases the strength and durability of whiffletrees, as it dispenses with pivot-bolt openings. It limits the swing of a whiffletree and dis-
5 penses with stay straps or chains, and it shifts the fulcrum-point toward the forward arm when a whiffletree swings, making the rear arm longer and increasing its leverage, so as to equalize the draft.
10 Changes in the form, proportion, and minor details of construction may be resorted to without departing from the spirit or sacrificing any of the advantages of this invention.

What I claim is—

15 1. In a device of the class described, the combination of a whiffletree having a straight rear edge, a straight rack-bar arranged at the front edge of the whiffletree, and a casing loosely receiving the whiffletree and comprising
20 top and bottom plates, a curved rear wall having a smooth inner convex face arranged to be engaged by the straight rear edge of the

whiffletree, and the front wall provided at its inner face with a curved rack meshing with the straight rack of the whiffletree, front and rear walls being formed integral with top and bottom plates, substantially as described. 25

2. In a device of the class described, the combination of a whiffletree provided with a straight rack at its front edge, and a casing 30 comprising top and bottom plates and curved front and rear walls, the top and bottom plates being extended beyond the front and rear walls, and the front wall being provided with a curved rack to mesh with the rack of the 35 whiffletree, substantially as described.

In testimony that I claim the foregoing as my own I have hereto affixed my signature in the presence of two witnesses.

WILLIAM W. FERREE.
